GARMENT FASTENING DEVICE

Frank E. De Long, Washingtonville, Pa.

Application February 15, 1932. Serial No. 593,097

5 Claims. (Cl. 24—228)

This invention relates to devices useful in fastening meeting or overlapping edges of garments of various kinds, particularly ladies' garments.

3 The object of the present invention is to provide a simple fastening device, of the character referred to, the component parts of which lend themselves to very economic manufacture in quantity from wire, and which are readily interengageable, but capable nevertheless, of effectively resisting accidental detachment in use.

As hereinafter disclosed, the fastening device of my invention is susceptible of many variations which are generally similar in that one of the two components affords a substantially rigid head, while the other component affords an eye which is adapted to engage the head of the first with a snap fit.

29 In the drawing hereunto attached Figs. I and II are perspective views of the component parts constituting one form of my improved fastening device.

Fig. III is a fragmentary illustration showing how the components of the device of Figs. I and II are secured to the opposing edges of a garment, and how they interengage to hold the garment in place; while,

Figs. IV, V, VI and VII are perspective views showing alternative forms of the two components of the device.

With reference first to Figs. I, II and III, the form of fastening device therein shown comprises two components which are respectively designated by the numerals 9 and 10. The component 9, it will be noted, is fashioned from a single piece of wire of predetermined length, with provision of an open shank portion 11 whereof the fold is twisted through an angle of ninety degrees and at the same time bent perpendicularly into the form of a substantially rigid upstanding crosswise circular loop-like head 12. The bars 13 constituting the shank 11 of the component 9, in this instance converge rearward to a point of meeting at 14 as shown in Figs. I and III, and have their ends curled in opposite directions with provision of anchorage loops 15 in the plane of said shank.

The companion component 10 is likewise fashioned from a single piece of wire with provision of a closed eye 16 beyond which the crossed ends of the wire are curved rearwardly away from each other as at 17, and curled outwardly at their termini to afford anchorage loops 18 in the same plane with the eye 16, the latter being so pro-

portioned as to engage the upstanding head 12 of the component 9 with a snap fit.

As shown in Fig. III, the two components 9 and 10 of the fastening device are adapted to be secured adjacent opposite meeting edges 19 and 20 of a garment after the manner of ordinary hooks and eyes, that is to say, by sewing, with the stitching 21 and 22 engaged through the anchorage loops 15 and 18 respectively of the components 9, 10. Due to the springiness of the wire from which the component 10 is made, its eye 16 is obviously given the capacity to yield to dilation incident to being forced over the upstanding head 12 of the component 9. Accordingly, the components 9, 10 are very easily interengaged but effectively resistive to accidental detachment in use.

In Fig. IV, the bars 13a constituting the shank 11a of the component 9a are paralleled and in direct contact, and the fold of the wire curled upwardly and inwardly toward the anchorage loops 15a to provide the upstanding head 12b.

The component 9b of Fig. V is constructed like the component 9a of Fig. IV, except that the upstanding head 12b is twisted at right angles to the shank 11b so as to lie crosswise of the latter.

In the alternative form of eye component 10a of Fig. VI the anchorage loops 18a are curled inwardly instead of outwardly as in the first described form shown in Figs. II and III.

Fig. VII shows a modified form of eye component 10b wherein the ends 17b of the wire of which it is made are directed laterally of the eye 16b, as a result of which the anchorage loops 18b are brought into line with the said eye.

The various described forms of the components of my improved fastening device are of course all made so as to be capable of interchangeable use one with another.

From the foregoing it will be seen that I have provided a very simple and inexpensive garment fastening device with parts which are very easily engaged, but which will effectively resist accidental detachment in use.

Having thus described my invention, I claim:

1. A garment fastening device comprising two components both made from individual lengths of wire suitably configured for attachment to the meeting portions of a garment, one of said components being formed with an upstanding loop head, and the other with a closed yieldable-eye for engaging the aforesaid loop head with a snap fit; and said second mentioned component being formed by medially fashioning the length of wire to provide a closed eye beyond which the crossed

wire ends are curved away from each other and curled at their termini into anchorage loops in the same plane with the closed yieldable-eye.

2. A garment fastening device comprising two components both made from individual lengths of wire, one component embodying an upstanding cross-wise loop-like head formed by a right-angled twist at the fold of a double-bar open shank with terminal anchorage loops fashioned by curling the free ends into contacting relation in the plane of said shank; and the other of said components affording a yielding eye for engaging the loop-like head of the first mentioned component with a snap fit, said second mentioned component being formed by medially fashioning the length of wire to provide a closed eye beyond which the crossed wire ends are curved rearwardly away from each other and curled outwardly at their termini into anchorage loops in the same plane with the yielding eye.

3. A garment fastening device comprising two components made from individual lengths of wire, one having a double bar shank with the fold of the wire curled into the form of a closed circular loop constituting an upstanding head in a plane crosswise of and at right angles to the longitudinal median of said double bar shank, the free ends of the bar shank being curled outwardly to provide terminal anchorage loops in the plane of said shank; and the other of said components affording a yielding eye for engaging the head of the first mentioned component with a snap fit, said second mentioned component being formed by medially fashioning the length of wire to provide a closed eye beyond which the crossed ends are curved rearwardly

away from each other and curled inwardly at their termini into anchorage loops in the same plane as the yieldable eye.

4. A garment fastening device comprising two components, both made from wire, one having a double bar shank with a contacting fold of the wire curled into a closed loop and twisted vertically-crosswise of the shank to constitute an upstanding head, the free ends of the shank bars being opposingly curled to form terminal anchorage loops in the plane of said shank; and the other of said components affording a yielding closed eye, by crossing the free portions thereof in divergent relation, for engaging the head of the double bar shank component with a snap fit, said second mentioned component also having anchorage loops in the plane of the eye at its termini formed by curling of the ends of the wire inwardly beyond said eye.

5. A garment fastening device comprising two wire components, a doubled bar shank portion with the fold looped over in alignment with the shank to provide an upstanding head and the opposing termini outwardly curled to form attaching eyes in the plane of said shank; the other of said components affording a yielding eye for engaging the head of the first component with a snap fit, said second mentioned component being formed by looping the wire length medially, crossing the free portions from which it is formed with the ends divergently-directed laterally in opposite directions from the eye, and said ends being individually curled at their termini with provision of substantially-aligned anchorage loops in the plane of said eye.
